UNITED STATES PATENT OFFICE.

MILO W. LOCKE, OF BALTIMORE, MARYLAND, ASSIGNOR OF ONE-HALF TO
R. SNOWDEN ANDREWS, OF SAME PLACE.

HOISTING AND CONVEYING APPARATUS.

SPECIFICATION forming part of Letters Patent No. 295,776, dated March 25, 1884.

Application filed January 17, 1884. (No model.)

To all whom it may concern:

Be it known that I, MILO W. LOCKE, a citizen of the United States, residing at Baltimore, in the State of Maryland, have invented new and useful Improvements in Hoisting and Conveying Apparatus, of which the following is a specification.

This invention has for its object to provide novel and efficient means for rapidly transporting heavy loads, such as stones, across rivers, ravines, or from one point to another; and to such end the invention consists in the mechanism hereinafter described and claimed, reference being had to the accompanying drawings, in which—

Figure 1 is a side elevation of an apparatus embodying my invention, parts being broken to better illustrate essential features; Figs. 2 and 3, detail sectional views of the gripping devices for stopping the car at any point on the cable trackway; Fig. 4, a detached perspective view of one of the gripping-jaws; Fig. 5, a diagram showing the arrangement of pulleys in the car and in the pulley or tackle block; and Fig. 6, a diagram showing a modification wherein an endless cable is used to draw the car back and forth on the cable, whether the latter be level or inclined.

Referring to the drawings, the number 1 indicates a wire cable, which is anchored at each end to extend across a river, ravine, or from one point to another, said cable, as in Fig. 1, standing in an inclined position, the highest part passing over a grooved wheel or other support, 2, in a trestle-work. A fall rope or cable, 4, passes over a grooved wheel, 5, in the trestle-work, and extends thence around a sheave in the carriage, 6, downward to and around a sheave in the tackle-block, 7, upward and around another sheave in the car, downward and around another sheave in the tackle-block, and thence upward to the car, where its extremity is permanently fastened to the car, all as clearly shown by the diagram Fig. 3. The tackle-block is provided at its upper end with a bolt or rod, 8, engaging a hook, 9, fixed to a rock-shaft, 10, journaled in cheek-pieces of the car, a lever, 11, being secured to the rock-shaft and extending in opposite directions therefrom, and having at each extremity a pendent cord or rod, by which the rock-shaft

is turned in its bearings to swing the hook for engaging it with or disengaging it from the bolt or rod of the tackle-block. The car or carriage 6 is provided with journaled grooved wheels 13 between its cheeks, which travel on the cable, and to one side of the carriage-frame is secured an arched brace or frame, 14, having a sleeve-bearing, 15, in which is arranged to rotate a shaft, 16, carrying at its outer end a grip-wheel, 17, and having a screw-threaded inner end engaging a screw-threaded collar, 18, to which are pivoted one end of two toggle-levers, 19, the other ends thereof being pivoted to the tail ends or shanks 20 of two cable-gripping jaws, 21, which are pivoted together at 22, and can be opened or closed to release or grasp the cable, according to the direction in which the grip-wheel is rotated. An endless hand-chain, 23, passes around the grip-wheel, for the purpose of actuating it to operate the gripping-jaws. By drawing on the endless chain to rotate the grip-wheel in one direction, the shanks or tails 20 will be drawn toward each other by the travel of the screw-collar on the threaded end of the shaft 16, thus releasing the jaws from their gripping action on the cable, while reverse movements of the parts mentioned will cause the jaws to grip and hold the cable, thereby stopping the carriage at any point thereon for the purpose of loading and unloading. The fall-rope 4 is to be connected at one end with a drum actuated by a powerful clutch-engine stationed at one end of the cable 1, so that by the fall-rope the carriage can be drawn along the cable after it has received its load, said fall-rope also serving to raise and lower the tackle or pulley block 7 when detached from the hook 9. The cable 1 is provided with fall-rope carriers 24, each in the form of two plates, carrying a pulley, 25, at their upper ends, which travels on the cable, and a pulley, 26, at their lower ends, on which the fall-rope rests. These carriers are connected together by cords 27, and the one nearest the carriage is connected therewith by a similar cord, 28. These carriers follow the carriage as it travels on the cable, and are stopped at regular intervals by the cords or chains 27 and 28, the object being to sustain the fall-rope and prevent it from sagging when paid out to permit the

carriage to travel on the cable. The load to be transported from a given spot to any desired place—say, for example, across a river or ravine—is secured to the hook 29 of the 5 tackle-block 7 through the medium of clamps, grapples, or other devices, the tackle-block having previously been disengaged from the hook 9 on the carriage and lowered to engage the load by paying out the fall-rope. The 10 clutch-engine is then operated to take up the fall sufficiently to elevate the tackle-block and cause the bolt or bar 8 thereof to engage the hook 9 on the carriage.

To limit the elevation of the tackle-block, 15 the fall-rope is provided with a spliced branch, 4^a, permanently connected with the carriage, and of such length that when the fall-rope has been taken up sufficiently to engage the tackle-block with the car the drawing action is re- 20 moved from the tackle-block and thrown by the branch 4^a onto the car, such branch by such time becoming taut, but hanging loose when the tackle-block is lowered to receive a load. The drum of the engine being operated 25 to wind up the fall-rope, the carriage is caused to travel along the cable until it reaches the point thereon where it is desired to stop the carriage for lowering the load, which is accomplished by drawing on the endless hand-chain 30 to turn the grip in the proper direction to cause the gripping jaws to seize and hold the cable, thus stopping the carriage, after which the proper cord or chain, 12, is drawn upon to rock the shaft 10 and cause the hook 9 to release the 35 tackle-block. The engine is then so operated that the fall-rope pays out and lowers the tackle-block and its load to the desired point, the pulley-block being then released from the load and raised to engage the hook on the car- 40 rige, after which the tackle-block is raised, engaged with the carriage, the gripping jaws released, the fall-rope paid out, and the car permitted to travel back along the cable for another load. The cable being inclined, the 45 carriage will rapidly travel back by gravity; but where the cable is inclined the load may be carried from the highest to the lowest part of the cable, or conversely, as desired. As the carriage travels back for another load, the 50 fall-rope carriers follow until stopped by their flexible connections 27 and 28, and when the carriage travels forward these carriers are successively moved forward by the same.

In Fig. 6 I have shown what may be termed 55 an "endless" rope, chain, or cable in connection with the fall-rope 4, whereby the carriage may be positively drawn in both directions along the cable. This permits the cable 1 to be placed level, if desired. This rope, chain, 60 or cable passes around a grooved wheel, 30, over pulleys 31, and around a double drum, 32, which will be connected with the engine by clutch devices, and the rope is connected at its two ends with opposite ends of the car- 65 rige. The turning of the drum winds and unwinds this rope and draws the carriage

along the cable as required, according to the direction in which the drum is turned by the engine. The fall-rope will of course perform its usual function of lowering and raising the 70 tackle-block.

Having thus described my invention, what I claim is—

1. The combination, in a hoisting and conveying apparatus, of a cable, a carriage to 75 travel thereon, gripping devices on said carriage for stopping and holding the carriage while both loading and unloading, a tackle-block, and a fall-rope connecting the carriage and the tackle-block, and serving to raise and 80 lower the latter, and also acting as a draft medium for moving the carriage on the cable, substantially as described.

2. The combination, in a hoisting and conveying apparatus, of a cable, a carriage to 85 travel thereon, gripping devices on said carriage for stopping and holding the carriage while both loading and unloading, a tackle-block, means whereby the tackle-block may be connected with and supported by the carriage, and a fall-rope connecting the tackle-block and carriage, and serving to raise and 90 lower the tackle-block, and also acting as a draft medium for moving the carriage on the cable, substantially as described. 95

3. The combination, in a hoisting and conveying apparatus, of a cable, a carriage to 100 travel thereon, gripping devices on said carriage for grasping the cable and stopping and holding the carriage while both loading and unloading, a tackle-block, means for detachably connecting the tackle-block with and supporting it on the carriage, and a fall-rope acting to move the carriage on the cable, and 105 also to raise and lower the tackle-block, substantially as described.

4. The combination of a cable, a carriage to 110 travel thereon having a swinging hook, a tackle-block having a bolt or rod to engage and disengage the hook, gripping devices on said carriage for stopping and holding the carriage while both loading and unloading, and a fall-rope for raising and lowering the tackle-block, and also serving as a draft medium for moving the carriage on the cable, substantially as 115 described.

5. The combination of a cable, a carriage to 120 travel thereon, a pulley-block detachably connected with the carriage, a fall-rope for moving the carriage on the cable and raising and lowering the pulley-block, and fall-rope carriers moving on the cable, substantially as 125 described.

6. The combination of a cable, a carriage to 130 travel thereon, a tackle-block, means for connecting the tackle-block with and supporting it on the carriage, and a fall-rope connecting the carriage and tackle-block to raise and lower the latter, and having a branch connected with the carriage, and of such length that when the tackle-block is raised sufficiently to engage it with the carriage the draft-strain

is thrown upon the branch to move the carriage on the cable, substantially as described.

7. The combination of the traveling carriage, the rock-shaft, the hook thereon, the 5 pulley-block having means to engage the hook, and the fall-rope connecting the carriage and pulley-block, for moving the carriage on its support and raising and lowering the pulley-block, substantially as described.

10. 8. The combination of a cable, a carriage to travel thereon, a rock-shaft mounted in the carriage and carrying a hook, arms extending from said shaft to rock it, a tackle-block having a bolt or rod to engage and disengage the hook, and a fall-rope passing around pulleys both in the carriage and tackle-block, and acting both to raise and lower the tackle-block, and to move the carriage on the cable, substantially as described.

15. 9. The combination of the cable, the carriage thereon, the cable-grip, the swinging hook on the carriage, the tackle-block having means to engage the hook, and the fall-rope for moving the carriage on the cable and raising and lowering the pulley-block, and having

20. 25. such length that when the tackle-block is raised and engages the hook the draft is thrown

upon the branch to move the carriage on the cable, substantially as described.

10. The combination of the cable, the carriage thereon, the tackle-block, means for detachably connecting the tackle-block with and supporting it on the carriage, the fall-rope connecting the carriage and tackle-block, to 35 raise and lower the latter, and also move the carriage on the cable, the gripping jaws pivoted directly on said carriage, the toggle-levers connecting the ends of the jaws, a screw-collar secured to the connected ends of the toggle-levers, the screw-shaft passing into the screw-collar, the grip-wheel on the screw-shaft, and means for operating the wheel, substantially as described.

11. The combination, with the cable or track 45 way, the carriage thereon, hoisting mechanism connected with the carriage, the fall-rope, and the endless rope or cable, substantially as described.

In testimony whereof I have hereunto set my 50 hand in the presence of two subscribing witnesses.
